**Henry T. King and Harold W. Pilkey, Detroit, Mich., as
signors to Chrysler Corporation, Highland Park, Mich.,
a corporation of Delaware**

Application June 11, 1956, Serial No. 41,825

Term of patent 7 years

(Cl, D48—32)

Fig. 1 is a front elevational view of an automobile lamp showing our new design;

Fig. 2 is a side elevational view thereof;

Figs. 3, 4, 5, 6, 7, 8, and 9 are sectional views taken on the lines 3—3, 4—4, 5—5, 6—6, 7—7, 8—8 and 9—9, respectively, of Fig. 1; and

Fig. 10 is a sectional view taken on the line 10—10 of Fig. 2.

The characteristic features of our design reside in the portions shown by means of full lines in the drawings.

We claim:

The ornamental design for an automobile lamp, substantially as shown and described.
